UNITED STATES PATENT OFFICE

155,540

DESIGN FOR A COAT

George Reiter, New York, N. Y.

Application December 3, 1948, Serial No. 149,953

Term of patent 3½ years

(Cl. D3—4)

To all whom it may concern:

Be it known that I, George Reiter, a citizen of the United States of America, residing in New York city, county of New York, and State of New York, have invented a new, original, and ornamental Design for a Coat, of which the following is a specification, reference being had to the accompanying drawing, forming part thereof, wherein,

I claim:

The ornamental design for a coat, substantially as shown.

GEORGE REITER.
